UNITED STATES PATENT OFFICE.

EDWARD H. SCHWARTZ, OF CHICAGO, ILLINOIS, ASSIGNOR TO THE HAWLEY DOWN DRAFT FURNACE COMPANY, OF CHICAGO, ILLINOIS, A CORPORATION OF ILLINOIS.

METHOD OF MELTING.

No. 871,071.

Specification of Letters Patent.

Patented Nov. 12, 1907.

Original application filed January 16, 1903, Serial No. 139,312. Divided and this application filed March 9, 1903.
Serial No. 146,909.

To all whom it may concern;

Be it known that I, EDWARD H. SCHWARTZ, residing at Chicago, Cook county, Illinois, have invented a certain new and useful Method of Melting, of which the 5 following is a specification.

My invention relates to a new and useful method of melting and treating with the head of gaseous flames various substances, such as metals of different kinds and their ores, and the like, as well as numerous non- 10 metallic substances. In fact, my method has numerous applications in different arts, and I contemplate practicing the same wherever applicable.

For the purpose of affording a clear and comprehensive understanding of my new method, I have herein shown- 15 a furnace in which the same may be suitably practiced, and, without intention of limiting my invention, I will proceed to describe such method in connection with this particular furnace.

In the drawings Figure 1 is a central vertical and 20 longitudinal section of a furnace in which my method may be practiced; Fig. 2 a cross-section thereof; and Fig. 3 a sectional plan view on line A—B of Fig. 1.

The furnace herein illustrated is of cylindrical form in general outline, comprising a cylindrical shell 1 and 25 truncated conical ends 2 and 3. A similarly shaped furnace chamber 4 is thereby formed, which chamber is lined with fire brick 5 or other proper refractory material. The furnace chamber has a top outlet 6 for the flames and products of combustion and a charging 30 opening 7 at one end and a pouring opening 8 at the other end. The furnace proper is intended to rock or oscillate in standards 9, to the end that the furnace may be oscillated for the effective operation of the furnace as hereinafter explained.

35 Through the top of the furnace, on opposite sides of the outlet 6, project burners 10, here shown as two in number, and suitably connected to a source of fuel supply. These burners are inclined toward each other in such manner as to direct, into the furnace chamber, 40 flames which converge or meet substantially at the central point of the furnace and substantially below the outlet 6. From this arrangement of the burners and from the shape of the furnace, there result two rotary flames on either side of the central vertical axis of the 45 furnace, all as illustrated in a general way, though crudely, by the arrows in Figs. 1 and 2. After the separate injected flames meet, as described, the single flame thus formed as the resultant is directed squarely toward or against the bottom of the furnace, that is at 50 substantially right angles thereto, and there split up or divided into two flames, owing to the striking of the hearth or the material thereon and also owing to the upwardly curved character of the ends of the hearth.

The flames then circle upwardly at opposite ends of the furnace chamber and being baffled or deflected by 55 the upper walls of the ends 2 and 3 of the furnace, such flames are doubled back and forced to make complete circles and again strike the hearth or material thereon before obtaining exit through the outlet 6.

In practice, the material to be melted or otherwise 60 treated is introduced into the furnace, preferably after a preliminary heating, and the burners are then started, with the result that the rotating flames hereinbefore described rapidly melt or reduce such material lying upon the bottom or hearth of the furnace. During this 65 period the charging opening and the pouring opening are both closed by their doors, with the result that the flames and products of combustion pass outward through the outlet 6. At the proper time, the furnace is tilted and the molten material poured through the 70 tap or pouring opening which has been opened for this purpose.

In some operations, particularly that of smelting, the furnace may be tilted to such extent that the charging opening approaches the vertical and such furnace 75 may thereupon be charged with the proper amount of ore and their fluxes. After the furnace is restored to its normal or desired working position, the ore will remain considerably banked up toward the right end of the furnace (Fig. 1) with the main body thereof above the 80 hearth, with the resulting advantage that the ore is better exposed to the flame, and, as melted, will run down upon the hearth. The molten material thus flowing to the hearth in comparatively thin streams will be highly heated by the flames and rendered quite 85 fluid. However, this particular method of melting is applicable to the melting of metals as well as to the melting and treatment of other substances. In fact, my method may be utilized for many different purposes and for the treatment of different materials, 90 whether metals, ores, or not, and I therefore contemplate practicing my method wherever applicable whether the operation be metallurgical or not; for instance, my method may be employed in the melting of glass, enamel and other non-metallic materials. 95

The burners 10 are supplied with fuel in any suitable way and as herein illustrated the burners are in communication with a fuel or oil supply pipe 11 and an air supply pipe 12, the air being preferably preliminarily heated by being caused to pass through a jacket or 100 chamber formed around the outlet 6. The fuel and air supply pipe have a suitable swing joint connection with stationary supply pipes as described in my original application filed January 16, 1903, Serial Number 139,312, of which application the present case is divisional. 105

I do not herein claim the apparatus or furnace in which my method is practiced, but the same forms the subject-matter of said original application.

I claim:

- 5 1. The method of melting or treating materials with heat which consists in combining a plurality of flame jets into a single flame which is projected at substantially right angles to the material and in direct contact therewith, and causing such flame to divide into two separate flames rotatively in a vertical plane in contact with the material; substantially as described.
- 10 2. The method of melting or treating materials with heat which consists in introducing through the top of a furnace chamber a plurality of downwardly directed flame jets which meet and combine into a single flame; causing such flame to impinge directly against the material and to thereupon divide into two separate flames rotating in a vertical plane in contact with the material and thence to pass outwardly from the furnace at a point adjacent the inlet of the flame-jets without interference therewith; substantially as described.
- 15 3. The method of melting or treating materials with heat within a furnace chamber which consists in banking up the material at one side of the hearth proper, and introducing into such chamber a plurality of flame jets directed against the hearth and caused to rotate in a vertical plane in contact with the banked up material which will be melted and will flow in a comparatively thin stream onto the hearth and be acted upon by the direct flame jets; substantially as described.
- 20 4. The method of melting materials in a furnace, which method consists in combining a plurality of flames into a

single flame projected substantially at right angles to the hearth of the furnace, causing such single flame to divide into two separate flames rotating in opposite directions, and removing the products of combustion from the furnace at a point adjacent the points of entrance of the flame or fuel.

35 5. The method of melting materials in a furnace, which method consists in combining a plurality of flames into a single flame projected substantially at right angles to the hearth of the furnace, causing such single flame to divide into two separate flames rotating in a vertical plane and in opposite directions, and removing the products of combustion from the furnace at a point between the points of entrance of the flame or fuel.

40 6. The method of melting or treating materials with heat consisting in combining a plurality of flame jets into a single flame which is directed downwardly substantially at right angles to the material, and causing such flame to divide into two separate flames whirling in a vertical plane and in a circle in contact with the material by impingement thereon and by movement at right angles thereto; substantially as described.

45 7. The method of melting or treating materials with heat consisting in combining a plurality of flame jets into a single flame which is directed downwardly substantially at right angles to the material, causing such flame to divide into two separate flames whirling in a vertical plane and in a circle in contact with the material, and removing the products of combustion at a point adjacent the entrance of the flame jets; substantially as described.

50 EDWARD H. SCHWARTZ.
